UNITED STATES PATENT OFFICE.

GEORGE W. RAUCH, OF ORRVILLE, OHIO.

SWEeper.

1,333,677.

Specification of Letters Patent. Patented Mar. 16, 1920.

Application filed December 7, 1918. Serial No. 265,704.

To all whom it may concern:

Be it known that I, GEORGE W. RAUCH, a citizen of the United States, residing at Orrville, in the county of Wayne and State 5 of Ohio, have invented new and useful Improvements in Sweepers, of which the following is a specification.

This invention relates to improvements in sweepers and has a special relation to 10 vacuum or motor operated sweepers.

The object of the present invention is to provide a sweeper of this character, which is of simple and durable construction and in which the motor which is utilized to operate the fan is protected from the action of the dirt. Another object is to provide a 15 sweeper having a brush which may be adjusted from the outside of the sweeper casing without lifting the latter from its operating position, thereby saving time and insuring a proper adjustment of the brush.

Another object is to provide novel means for regulating the distance of the nozzle or dirt opening from the floor, the said means 25 comprising adjustably mounted supporting rollers which regulate the height of the casing or nozzle.

Other objects and advantages of the invention will appear as the following description is read in connection with the accompanying drawings.

In the drawings:

Figure 1 is a side elevation of a sweeper embodying the present invention.

35 Fig. 2 is a front view of the same.

Fig. 3 is a vertical section taken from the front to the rear of the sweeper.

Fig. 4 is a similar view taken at right angles to Fig. 3.

40 Fig. 5 is an enlarged vertical sectional view through the adjustable brush bearing.

Fig. 6 is an enlarged transverse sectional view through this bearing.

Fig. 7 is a detail section illustrating the 45 securing means for the adjustable yoke which carries the supporting rollers.

Fig. 8 is a detail view of the filtering screen securing means.

Referring in detail to the drawings, like 50 characters of reference denote corresponding parts throughout the several views.

In the embodiment of the invention illustrated, there is provided a casing 10, which

is preferably rectangular in form. This casing is provided with the usual opening or 55 nozzle 11 for the passage of dirt or dust.

Secured to each side of the end of the casing opposite the nozzle 11, is a supporting roller 12, the latter being mounted upon a short shaft 13. Mounted for pivotal movement upon each of the shafts 13, is one end of a yoke 14 which extends forwardly or toward the nozzle end of the casing and across said end. Carried by the yoke and positioned adjacent the nozzle or forward 60 end of the casing are supporting rollers 15, so that there are provided four rollers which act to support the sweeper in operation. The yoke 14 is capable of adjustment upon the adjustment upon the shafts 13 so as 65 to bring the forward or nozzle end of the casing closely to or farther away from the floor and in order to hold the yoke in the desired position, there is provided a set screw 16, which is carried by the casing 70 and which operates in a slot 17 provided in the yoke.

Mounted within the casing is a brush 18, which is journaled in bearings at each end of the casing. These bearings are adjustable and consist of plates 19 which are 75 slideable in guides 20, the adjustment of the said plates being regulated through the medium of screws 21 extending upon the outside of the casing. This permits of the adjustment 80 of the brush so as to regulate its contact with the floor without lifting the sweeper. The plates 19 are engaged by flat springs 22, whose tension is regulated by means of a screw 23. The brush 18 is connected to 85 the bearing plates 19 by means of a stud 24, which extends inwardly toward the brush and engages the ends thereof through the medium of a dust proof anti-friction bearing 25, which is capable of adjustment 90 to take up wear.

Mounted upon the brush at a point approximately midway between its ends, is a metal disk 26, which is engaged by a fiber roller 27, the latter being mounted upon the 100 end of a shaft 28 of the motor 29. By this means the brush is rotated, the roller 27 frictionally engaging the disk 26, this driving means permitting of the adjustment of the brush in the manner previously mentioned.

The motor 29 is preferably of the electric type and is engaged in the usual manner to a suitable source of energy and is controlled by a switch 30. The motor 29 also operates a fan for the purpose of creating suction through the nozzle 11 and deposits the same within the casing, and as the motor 29 is positioned above the casing, it is protected from the action of the dirt. Located at the rear of the machine, or at the end of the casing opposite the nozzle 11, is an opening 32 which is surrounded by frame 33, the latter being covered with a screen and dust proof cloth so as to permit of the passage of air and at the same time retain the dirt and dust within the casing. The frame 33 is suitably secured to the casing and may be provided with a suitable fastening device to permit of the frame being used as a door for the removal of the contents of the casing. The frame 33 is provided with a felt band or a lining 34 so as to provide a dust proof joint.

The invention is susceptible of various changes in its form, proportions and minor details of construction, and the writer is herein reserved to make any changes that

fall within the scope of the claims hereto appended.

Having described my invention, what is claimed is:

1. The combination with a sweeper including a brush located near one end of the casing, of supporting wheels for said casing, a frame pivotally mounted upon the axles of the wheels at one end of the casing and carrying wheels at the opposite or brush end thereof, and means for adjusting the frame to regulate contact of the brush with the floor.

2. A sweeper comprising a casing provided with an opening, motor operated means for causing a suction through said opening, a brush located within the casing and extending through said opening, a slide adjustably mounted upon the outside of the casing at each end of the brush, a bearing carried by each of said slides for receiving the brush, a reduced neck for said bearing for movement in an opening in the casing and a spring surrounding said neck and engageable with the casing.

In testimony whereof I affix my signature.

GEORGE W. RAUCH.
